UNITED STATES PATENT OFFICE.

PETER SARTORY, OF BAYSWATER, LONDON, ENGLAND.

EXOTHERMIC HEATER.

Original application filed August 4, 1924, Serial No. 730,122. Divided and this application filed December 24, 1924. Serial No. 757,934.

To all whom it may concern:

Be it known that I, PETER SARTORY, a subject of the King of Great Britain and Ireland, residing at Bayswater, London, England, have invented certain new and useful Improvements in Exothermic Heaters, of which the following is a specification.

This invention relates to heaters used in steaming tubes when steaming a tress of hair arranged upon a curler.

Heretofore it has been usual to embody in the steaming tube an electrical resistance which when connected to an external electric supply provides the necessary heat for steaming the tress of hair.

The object of the present invention is to provide an autogenous heater in which the heat required for the steaming operation is obtained by exothermic reaction.

Another object is to obtain such a heater in which water is one reagent, whereby the other chemical substance with which the water is to react to produce the heat required, can be placed in the heater during manufacture, and the water brought into contact with the substance when the heater is disposed in a heating tube.

According to the invention an exothermically operating heater for use in steaming a tress of hair coiled upon a curler, comprises a stratum of a chemical material which will react exothermically with a liquid reagent, formed to extend lengthwise of the tress to be steamed, and a juxtaposed fibrous stratum which is capable of acting as a distributor of a liquid reagent to the chemical material which reacts exothermically with said material.

The accompanying drawings illustrate preferred constructions according to this invention.

Figs. 1 and 2 are plan and cross sectional views of one form of chemical heating pad in accordance with the present invention.

Figs. 3 to 6 inclusive illustrate a means of applying such heating pad in order to effect the steaming of a coiled tress of hair; Figs. 3 and 4 being respectively longitudinal and cross sectional views showing the pad applied to a coiled tress of hair, and enclosed in a steaming tube, together with an absorbent pad for applying moisture to the heating pad, while Figs. 5 and 6 are respectively external end and side views of the steaming tube, and

Fig. 7 is a side view partly in section of one form of tubular chemical heating pad in accordance with the present invention.

Referring to Figs. 1 and 2, 1 indicates a heating pad or jacket comprising a porous envelope of cheese cloth, paper or the like divided into pockets by rows 2 of stitching, and provided with a flap or extension 3; the pockets being filled with powdered or granular calcium oxide, indicated at 4.

In Fig. 3 the pad illustrated at Figs. 1 and 2 is shown applied to a tress of hair arranged upon a curler 6, the chemical material being supported by the porous fabric of which the envelope is made, the flap 3 being first wrapped round the curled tress to protect it from contact with the material 4, and also forming a lining to the pad. This lining gives additional protection to the tress treated without stiffening the envelope.

As shown, water is applied to the heating pad by enveloping the same in cotton wool or like fibrous material 7, such as can be saturated with water, and which may be in the form of pads; the whole being enclosed in a steaming tube 8 of compressed fibre or other material. Such an arrangement provides a heater having an inner annular layer of chemical material and an outer layer of fibrous material.

The steaming tube 8 is divided longitudinally, as indicated at 9 (Fig. 6), each section having a slotted end plate 10 adapted to embrace the root end of the tress, the sections of the steaming tube being detachably held together by a clip 11 preferably secured to one section.

When the tube is assembled it compresses the saturated pads 7, so expressing the water into the heating material 4 of the pad or jacket 1 whereby an exothermic reaction is initiated, which develops sufficient heat for steaming the enclosed tress without risk of injury to the hair.

If desired a split rubber disc 12 of known form may be secured over the ligament or projecting end of the tress to prevent steam from injuring the scalp, while the other end of the tube 8 may be left open, as shown.

Referring to Fig. 7, the heating pad 1 is arranged as a tubular member, and is carried on a skeleton member in the form of a light perforated tube 13 of cylindrical section, which may be of metal, and which, with the fabric material of the envelope,

acts as a support for the chemical material; the pad 1 being enveloped in an absorbent layer 7 secured by ties 7a.

- Such a heater can be packed up in boxes 5 as refills for steaming tubes constructed as herein described, or as described in copending application Serial No. 730,122, and my copending application 757,935 for "Improvements in steaming tubes".
- 10 By the present invention a process of curling and waving human hair on the head is obtainable wherein the heat required for steaming is generated locally, thereby eliminating any external source of heat energy,
- 15 e. g., electric power units.

I claim:

1. An exothermically operating tubular heater for use in a steaming tube when steaming a tress of hair arranged upon a 20 curler, comprising in combination a skeleton member of cylindrical section, a porous envelope carried by said skeleton member, a chemical substance in the envelope and a layer of fibrous material on the outside of 25 said envelope, the chemical material being such as to react exothermically with a liquid and the fibrous material being capable of acting as a distributor of the liquid reagent to said chemical material.
- 30 2. An exothermically operating tubular heater for use in curling and waving human hair upon a curler, comprising the combination with a support including a skeleton member of cylindrical section, and 35 a porous fabric covering said member, of a layer of chemical material surrounding

said fabric, and a layer of fibrous material surrounding the chemical layer, such chemical material being such as to react exothermically with a liquid, and the fibrous material being capable of acting as a distributor of the liquid to the chemical layer.

3. An exothermically operating tubular heater for use in steaming a tress of hair comprising in combination an inner layer 45 of chemical material contained within a supporting porous envelope, a flap to said envelope forming a lining to said heater, and an outer layer of fibrous material, the chemical material being such as to react 50 exothermically with a liquid and the fibrous material being capable of acting as a distributor of the liquid reagent to said chemical material.

4. An exothermically operating tubular 55 heater for use in a steaming tube when steaming a tress of hair arranged upon a curler, comprising in combination a skeleton member of cylindrical section, a porous envelope carried on said skeleton member, 60 a chemical substance in the envelope, a marginal flap to the envelope disposed and large enough to form a complete lining to the envelope when carried on the skeleton member, and a layer of fibrous material on 65 the outside of said envelope, the chemical material being such as to react exothermically with a liquid and the fibrous material being capable of acting as a distributor of the liquid reagent to said chemical material.

In testimony whereof I affix my signature.

PETER SARTORY.
